UNITED STATES PATENT OFFICE.

CHARLES E. SCHEER, OF WASHINGTON, DISTRICT OF COLUMBIA.

VALVE.

1,249,837.

Specification of Letters Patent.

Patented Dec. 11, 1917.

Application filed March 2, 1916. Serial No. 81,573.

To all whom it may concern:

Be it known that I, CHARLES E. SCHEER, a citizen of the United States, residing at Washington, in the District of Columbia, 5 have invented new and useful Improvements in Valves, of which the following is a specification.

The present invention relates to improvements in valves.

10 The primary object of the invention is the provision of a valve having an inlet and two outlet openings formed therein and means within the same for shutting off the inlet and both outlets or either one of said outlets 15 and leaving open the inlet and the other of the outlets.

Another object of the invention is the provision of a valve including a casing having inlet and outlet openings formed therein, 20 and a hollow plug valve having openings in its wall corresponding to the inlet and outlet openings of the casing, whereby the flow of fluid through the inlet and outlet openings can be easily controlled.

25 A further object of the invention is the provision of a valve such as above described which will be comparatively simple and inexpensive to manufacture, reliable and efficient in use, requiring but few parts and 30 which is easily operated.

With the above and other objects in view the present invention resides in the novel features of construction, formations, combinations, and arrangements of parts to be 35 hereinafter more fully described, claimed, and illustrated in the accompanying drawing forming a part of this application, it being understood in this connection that various minor changes in the details of construction, can be resorted to within the scope 40 of the appended claim without departing from the spirit of the invention or sacrificing any of the advantages thereof.

In the drawing:

45 Figure 1 is a top plan view of the invention showing the inlet and outlet pipes broken off.

50 Fig. 2 is a horizontal sectional view showing the inlet and both outlets in open position.

Fig. 3 is a similar view showing the inlet and horizontal outlet in open positions, and the vertical outlet closed.

Fig. 4 is a similar view showing the inlet and vertical outlet in open positions and 55 the horizontal outlet closed.

Fig. 5 is a vertical sectional view taken at right angles to Figs. 2, 3 and 4 showing the valve in a position similar to that shown in 60 Fig. 2.

Fig. 6 is a transverse sectional view taken through the major end of the plug which is removed from the casing.

Fig. 7 is a similar view taken through the minor end thereof.

Referring to the accompanying drawing by corresponding characters of reference throughout the several views, the numeral 8 designates in general my improved valve, which consists of a casing 9 chambered as 70 shown at 10 to receive a tapered hollow plug 11. The casing 9 is provided with oppositely extending side nipples 12 and 13 and an upwardly extending vertical nipple 14 for connection respectively with the inlet 75 pipe 15 and outlet pipes 16 and 17.

Passages 18, 19 and 20 lead from the open ends of the nipples 12, 13 and 14 and communicate with the central chamber 10 of the 80 casing.

One end of the valve casing 9 is formed with a circular bead or flange 21 provided with graduation marks 22 to register with the projections or fingers 23 formed upon the major end of the plug 11 which is likewise provided with a handle 24 by means of which the plug 11 can be rotated for a purpose to be later explained.

As shown in the accompanying drawing the handle 24 is preferably cast integrally 90 with the plug 11 which is provided at its opposite or minor end with a threaded stem 25 projecting a suitable distance beyond the opposite end of the casing 9 for engagement with a nut 26 by means of which the plug is 95 held in position.

The minor end of the plug 11 extends slightly beyond the adjacent ends of the casing 9 and seats within a recess 27 formed in one side of a washer 28 which, when the nut 100

26 is tightened is forced against the plug and all adjacent portions of the casing 9 sealing the latter against leakage.

The major end of the hollow plug 11 is 5 provided with openings 29 and 30 arranged at approximately ninety degrees relative to each other and adapted to register with the before described passages 19 and 20 in the casing.

10 The opposite or minor end of the plug is provided with openings 31, 32 and 33 which are adapted to register with the inlet passage 18 of the casing.

The openings from 29 to 33 inclusive obviously communicate with the passages from 15 to 20 inclusive and by the proper manipulation of the handle 24, as will be hereinafter more fully described, control the flow of the fluid into the casing 9 through the inlet 15 and out through the outlets 16 and 17.

The operation of the device is as follows: When it is desired to open the inlet and both of the outlets the handle 24 is moved to the position shown in Figs. 1 and 2. When in 25 this position it will be apparent that the inlet passage 18 of the casing registers with the opening 32 in the valve and further that the passage 19 in the casing registers with the opening 30 in the valve while the passage 30 20 in the casing registers with the opening 29 in the valve. This permits the water to pass into the casing through the inlet pipes 15 and out again through the outlet pipes 16 and 17.

35 When it is desired to shut off the flow of water through the pipe 17 the valve 24 is given a quarter turn in the direction of the arrow shown in Fig. 1.

This operation moves the opening 29 in 40 the plug into registration with the opening 19 and likewise moves the opening 33 into registration with the passage 18 which permits the water to flow into the casing through the pipe 15 and out again through 45 the pipe 16, thus closing the passage 20 and shutting off the flow of water through the pipe 17.

A quarter turn from the initial position shown in Figs. 1 and 2, in the direction of the arrow shown in Fig. 2, moves the plug 11 50 so that the opening 31 will register with the passage 18 and the opening 30 with the passage 20. This shuts off a flow of water through the passage 19 and pipe 16 and permits the water to flow into the casing 55 through the pipe 15 and out through the pipe 17.

When the plug is in the position shown in Fig. 4 a quarter of a turn in the direction indicated by the arrow shuts off not only the 60 outlet passages 19 and 20 but likewise the inlet passage 18.

From the foregoing description taken in connection with the accompanying drawing it will be manifest that a valve is provided 65 which will fulfil all of the necessary requirements of such a device.

Having thus fully described the invention, what I claim as new and desire to protect by Letters Patent is:

In a valve such as described, the combination of a casing having a central tapered recess formed therein, said casing having an inlet and an outlet passage leading from the opposite sides thereof to the opposite ends of 75 the tapered recess, a hollow plug valve disposed within said recess and having three inlet openings provided therein for registration with the inlet opening in said casing, and two outlet openings formed in one end 80 thereof for registration with the outlet opening, said inlet and said outlet openings in the valve being each disposed in the same horizontal plane and being so positioned that by a partial turn of said valve any one of said 85 inlet openings can be brought into registration with the inlet passage of the casing and one of the outlet openings brought into registration with the outlet passage or said passages can be entirely cut off. 90

Signed at Washington, in the District of Columbia this 25th day of February, 1916.

CHARLES E. SCHEER.
